UNITED STATES PATENT OFFICE.

MAURICE LACHMAN, OF NEW YORK, N. Y., ASSIGNOR, BY MESNE ASSIGNMENTS, TO BETHLEHEM STEEL COMPANY, OF BETHLEHEM, PENNSYLVANIA, A CORPORATION OF PENNSYLVANIA.

METAL WHEEL.

1,378,877.

Specification of Letters Patent. Patented May 24, 1921.

Application filed August 19, 1918. Serial No. 250,428.

To all whom it may concern:

Be it known that I, MAURICE LACHMAN, a citizen of the United States, and a resident of New York, in the county of New York and State of New York, have invented certain new and useful Improvements in Metal Wheels, of which the following is a specification.

My invention relates to the construction of metal wheels and its object is to so construct the wheel that it may be made up largely from sheet metal and so that at the same time it shall be of great strength and rigidity and capable of effectively resisting torsional strains.

My invention relates principally to the spoke portion of the wheel or that portion which connects the hub and rim.

Another object of the invention is to so construct the wheel that the main portions, after suitable assembly, may be secured together by one operation in a press or machine adapted to weld them together.

Other features of the invention relate to the manner of construction when the spoke portion is closed in by disks or plates connecting the rim and hub which give the appearance of a disk wheel and in part contribute to the strength of the wheel if desired.

The invention consists of the features of construction and combinations of parts particularly hereinafter described and then pointed out in the claims.

35 In the accompanying drawing:

Figure 1 is a side elevation (partially in section) of a portion of my improved wheel.

Fig. 2 is a horizontal cross-section on the line 2—2 of Fig. 1.

40 Fig. 3 is a view similar to Fig. 2 showing a modification of the invention.

Fig. 4 is a perspective view of a portion of one of the side plates.

45 Fig. 5 illustrates a further modification of the invention.

Referring more particularly to the drawing:

1 indicates a one piece metal rim having inwardly extending flanges 1' at both edges 50 and integral therewith. 2 indicates a sheet

metal strip or strips constituting wholly or in part the spoke portion of the wheel. The sheet metal of this portion of the wheel is arranged as shown with the plane of the sheet transverse to the plane of the wheel 55 and with the free edges of the sheet metal presented to the sides of the wheel and forms the spoke element proper which transmits the load from spoke to rim. By preference the element 2 is made of one or more strips of sheet metal bent into zig-zag form and with the loops at the periphery bearing directly against the inner surface of the rim at which point said loops take the form of an arc the same as the arc of the inner 60 circumference of the rim where they engage thereby giving a wide or extended bearing surface between them. The loops at the inner or hub portion of the zig-zag may have similar bearing if desired on the barrel of 65 the hub.

Preferably for simplicity and cheapness of construction the element 2 is made of a single strip of metal whose ends are welded together as at point 2'. The element 2 75 formed as shown for the completed wheel being made of sheet metal may be sprung into place between the flanges of the rim.

3 indicates sheet metal side plates of any desired number applied to the edges of the 80 element 2 and directly welded by their inner surfaces to said edges preferably by electric welding. Said side plates are preferably in the form of annuli and to assist in welding each may be provided with a ridge 3' projecting from its inner surface to engage the edge of the sheet metal forming the spoke portion 2 thereby forming limited areas of contact suitable for an electric welding operation.

90 As will be seen, by assembling the parts 1, 2, 3 in a welding machine in the relation shown, the plates 2 and 3 may be readily welded together at points of engagement of the inner surface of 3 with the edge of 2 by 95 compressing the assembled structure between suitable welding dies.

The side plates 3 of which there may be any desired number strengthen and reinforce the spoke portion of the structure and 100

hold the parts of the element in fixed relation. The inner one of the plates 3 forms in effect the side plate or flange of the wheel hub.

- 5 The complete structure described is closed in by the sheet metal disks 4 extending from hub to rim. These disks, at their outer edge, meet the edge of the flanges at 5 where the flange and disk edge may, if desired, be
 10 welded or brazed together by any desired means. The body of the sheet metal disk is preferably fastened at intervals by spot welds indicated at 6 to the spoke portion of the structure. If desired, these welds might be
 15 made at the same time that the annuli 3 are welded to the sheet metal spokes by assembling them all together in the welding machine, applying pressure and electric current, the disk having been previously provided with suitable welding points or projections on its interior surface preferably in line with the points of welding between 2 and 3. Or the pressure die might be provided with welding electrodes or points at
 25 the desired positions of the welds between 4 and 3.

7 indicates suitable reinforcing plates located in the rim and bridging the flanges of the rim. These may be suitably fastened in position by securing them to the loops of the bent spoke element 2 or otherwise and serve to additionally strengthen the rim part of the wheel.

As will be seen, the ends of the reinforcing plates 7 may form a bearing for the edges of the closing disks 4. To further secure the spoke element 2 in position the arc of the loop bearing against the inner surface of the rim may be spot welded or otherwise secured thereto.

In the modification of my invention illustrated in Fig. 3 the meeting edges of the flanges on the rim and the disk are secured together and the joint between them closed and detachment of the closure disk prevented by expanding the edge of the peripheral flange on the disk under the edge of the flange on the rim and by further, if desired, spinning over the edge of the flange 45 on the rim upon said edge of the disk. This will securely fasten the closing disk against detachment. If desired, welds between the body of the disk and the spoke structure may be omitted.

55 Fig. 5 shows a modification in the manner of joining the side plate and flange of the rim at their meeting point by turning over or spinning down the free edge of the plate upon the outside of the flange.

60 What I claim as my invention is:

1. A metal wheel the spoke portion of which consists of a sheet metal plate having a free edge of the sheet metal presented to the side of the wheel combined with a sheet

metal side plate circumferentially continuous between the hub and rim and welded by its inner surface to the free edge of the sheet metal plate of which the spoke portion consists.

2. A metal wheel having a spoke portion 70 consisting of a sheet metal plate having the free edge of the sheet metal presented to the side of the wheel combined with an annulus of sheet metal welded by its inner face to the edge of the said sheet metal plate between the hub and rim.

75 3. In a metal wheel, a spoke portion consisting of a sheet metal plate having the free edge of the sheet metal presented to the side of the wheel combined with a metal 80 side plate having an annular ridge welded to the edge of the sheet metal forming the spoke portion.

85 4. In a metal wheel, a spoke portion comprising a sheet metal plate bent into zig-zag form and having the plane of the sheet transverse to the plane of the wheel and having loops following the contour of the rim and engaged with the inner surface thereof.

90 5. A metal wheel having a spoke portion consisting of a plate of sheet metal bent into zig-zag form with the plane of the plate transverse to the plane of the wheel combined with circumferentially continuous 95 sheet metal side plates welded by their inner surfaces to the free edge of the plate forming the spoke portion.

100 6. A metal wheel comprising a metal rim having at its opposite edges inwardly directed flanges integral therewith and a spoke portion comprising an endless strip of sheet metal bent into zig-zag form and embraced between said flanges.

105 7. A metal wheel whose spoke portion embodies a strip of sheet metal having edges presented to the sides of the wheel, sheet metal side plates engaging the edges of said strip and welded thereto on their inner surfaces, a flanged metal rim embracing said 110 spoke portion by its flanges and metal disks inclosing the spoke portion and side plates and having a peripheral edge meeting said flanges.

115 8. A metal wheel whose spoke portion embodies a strip of sheet metal having edges presented to the sides of the wheel, sheet metal side plates engaging the edges of said strip and welded thereto on their inner surfaces, a flanged metal rim embracing said 120 spoke portion by its flanges and metal disks inclosing the spoke portion and side plates and having a peripheral edge meeting said flanges and fastened to said side plates.

125 9. A metal wheel comprising sheet metal forming a spoke portion and having opposite edges presented to the sides of the wheel, annular sheet metal plates engaging

the edges of the sheet metal forming the spoke portion and secured thereto, a metal rim and disks inclosing the spoke portion and side plates the edges of said disks meeting the edges of the rim to form a closure of the spoke structure.

Signed at New York, in the county of

New York, and State of New York, this 16th day of August, A. D. 1918.

MAURICE LACHMAN.
